UNITED STATES PATENT OFFICE

BEN DOMONT, OF INDIANAPOLIS, INDIANA

DESIGN FOR A BOTTLE OR THE LIKE

Application filed July 17, 1931. Serial No. 40,579. Term of patent 7 years.

To all whom it may concern:

Be it known that I, BEN DOMONT, a citizen of the United States, residing at Indianapolis, in the county of Marion and State of Indiana, have invented a new, original, and ornamental Design for a Bottle or the like, of which the following is a specification.

The invention is illustrated in the accompanying drawings in which

Fig. 1 is a front view of a bottle embodying the design and Fig. 2, a rear view of the bottle.

The surface of the bottle is pitted and orange colored similar to the surface of an orange.

I claim:

The ornamental design for a bottle or the like as shown and described.

In testimony whereof I affix my signature.

BEN DOMONT.
